REFRIGERANT CONTAINER

Charles D. Bonsall, Chicago, Ill., assignor, by
mesne assignments, to Standard Railway De-
vices Company, a corporation of Delaware

Application December 11, 1939, Serial No. 308,534

8 Claims. (Cl. 62—17)

This invention relates to refrigerator cars used to transport perishable commodities at a predetermined temperature. The essential features of a refrigerator car are an insulated body to prevent or retard ingress of heat during warm weather and egress of heat during cold weather and a cooling means and a heating means to be used during warm and cold weather respectively.

This invention applies particularly to cars in which the cooling means, preferably containers for water ice, eutectic ice, brine or dry ice, are disposed immediately below the roof of the car. The lading is supported in spaced relation to the floor by a foraminous rack. Flues, preferably associated with the side walls of the car, communicate between the cooling means and the space under the floor rack to provide a path for the circulation of air. The path is from the cooling means downwardly through the aforementioned flues, through the space under the floor rack, upwardly through the lading compartment, thereby cooling the lading, and finally to the cooling means from where the cycle is repeated.

An object of the invention is to provide a refrigerant container, which embodies both light weight and the strength to carry a large mass of refrigerant, and which may be conveniently installed as a unit. A further object is to adapt the container to be supported between spaced apart carlines extending between the opposite side walls of the car.

Another object is to design the refrigerant containers so that the cleaning thereof is relatively easy, preferably by providing readily removable parts, such as the tops. A further object is to provide for the certain retention of a limited amount of liquid within the containers.

The invention has for another object the provision of reinforcing members for the bottom and walls of the container, which members are disposed within the container to retard surging of the refrigerant due to service movements of the car. A further object is to position the reinforcing members so that a refrigerant may be loaded through an opening in the top of the container and easily distributed to all parts of the container.

Another object of my invention is to provide a container, which may be readily galvanized or coated with other protecting materials. It is well known that articles made of materials having a large variation in thickness or material severely stressed due to deformation, have a pronounced tendency to warp when heated or cooled. Con-

sequently, I minimize such warping by eliminating the causes thereof, noted hereinabove.

Another object is to facilitate the assembly of the container. The adjacent edges of the sheets comprising the container are flanged outwardly in flatwise contacting relation, which relation permits the ready insertion of bolts, easy welding at the edges or the use of rivets wherein the jaws of a compression type riveter may straddle the flanges for the purposes of forming the rivet heads.

Other objects and advantages of my invention will be apparent from the following detailed description by referring to the accompanying drawings.

In the drawings:

Fig. 1 is a transverse section of a refrigerator car showing the adaption of my refrigerant container to an overhead bunker refrigerator car.

Fig. 2 is an end elevation view of the container shown in Fig. 1.

Fig. 3 is a section on line 3—3 of Fig. 1.

Fig. 4 is a plan view with the upper portion partly broken away, of the refrigerant container shown in Figs. 1 to 3.

Fig. 5 is a longitudinal sectional view of a modified form of container, the view being similar to a portion of Fig. 3.

The general parts of the refrigerator car shown are insulated roof 2, side wall 3, floor 4, hatch 5, refrigerant container 6, side wall flue 7, foraminous floor rack 8 and space 9 between rack 8 and floor 4. A refrigerant container 6 is positioned directly below the roof 2 and adjacent the side wall 3. A drip pan 12 is provided below the container 6 and a partition 14 is secured in an upstanding position at the edge of the drip pan 12. The drip pan 12 and partition 14 cooperate with the roof 2 and side wall 3 to form an enclosing structure 11 around the container 6, an air inlet opening 15 being provided by spacing the partition 14 from the roof 2. An air discharge opening 17 which leads to the flue 7 is formed by spacing the drip pan 12 from the wall 3.

Air circulation is as follows: Air in the lading compartment 18 is warmed by contact with the lading and rises to enter the enclosing structure 11 through the air inlet opening 15. The air is cooled by contact with the refrigerant container 6 and falls by reason of its greater density through the discharge opening 17 and flue 7 to the space 9 whence it rises through the rack 8 to the lading compartment 18. Cars of this type usually have a row of refrigerant containers near each side wall and directly below the roof so that

air flowing from the lading compartment flows between the containers disposed on opposite sides of the car.

The refrigerant container 6 is preferably a tank having a lower portion 25 and an upper portion 26. The lower portion 25 comprises a bottom 28 having spaced apart side walls 29 upstanding therefrom and preferably formed integral therewith. The upper edges of the side walls 29 are provided with outstanding marginal flanges 30. The ends of the tank are preferably comprised of substantially vertical walls 32 having outstanding peripheral flanges 34. The peripheral flanges 34 are in flatwise contact with the bottom 28 and side walls 29 and are secured thereto by some means, such as the rivets 36 shown in Figs. 2 and 3, the weld 37 shown in Fig. 5, or bolts inserted in the same manner as the rivets 36.

The upper portion 26 preferably comprises a top 40 having depending side marginal flanges 42 and outstanding reflanges 44. The reflanges 44 are adapted to engage flatwise with the flanges 30 and are secured thereto, preferably by a readily removable means, such as the bolts 45 or rivets. The top 40 is secured to the flanges 34, preferably by the bolts 46. Welding may be used in cases where it is not required that the upper portion 26 be removable. The bottom 28 and the major portion of the top 40 are preferably disposed in planes, substantially parallel, but converging slightly toward a side wall 47, an opening 48 having an upstanding peripheral stiffening flange 49 is provided in the top 40 for loading refrigerant into the tank.

Substantially vertical baffle plates 55 are provided within the tank 6, for both the reinforcement thereof and to prevent surging of a refrigerant therewithin. The baffle plate 56 extends between the end walls 32 and is secured thereto by the flanges 58 and rivets 60 as shown in Figs. 3 and 4 or by the weld 61 shown in Fig. 5. The baffle plate 64 extends between and is secured to the side walls 29 by the riveting or welding means hereinabove described in reference to the baffle 56. In the construction as actually shown, the baffle plate 56 consists of two parts 66, each extending between the baffle plate 64 and an end wall 32. The baffle plates 56, 64 are preferably spaced from the bottom 28 of the tank 6 and secured thereto at intervals by the spaced apart angle shaped clips 68 riveted to both baffle plates 56, 64 and the bottom 28. An alternate construction is shown in Fig. 5 wherein the baffle plate 70 has upper portions 71 spaced from the bottom 28 and lower portions 72 secured thereto, as by the welding 73 shown in Fig. 5, or flanges 75 and rivets 76 as shown in Figs. 1, 3 and 4. An advantage claimed for the welding method shown in Fig. 5 over the riveting is that acid used for pickling prior to galvanizing, may become lodged behind the flanges with consequent damage to the ensuing galvanize coating.

The intersection of the baffle plates 56, 64 is preferably arranged to be below the opening 48 so that refrigerant may be conveniently loaded through the opening to each of the sections formed by the baffle plates. A plurality of apertures 80 are preferably provided in the side wall 47 for overflow of liquid to cool the air circulating through the flue 17, said apertures being disposed below the flanges 30 to prevent seepage of the liquid between the flanges 30 and reflanges 44 with consequent corrosive damage to the bolts 81. As shown in Fig. 3, the apertures 80 are grouped near the center of the tank 6 and the portions 75

of the side walls 29 adjacent the end walls 32 are substantially imperforate so that when a liquid refrigerant surges against the end walls 32 during service movements of the car, the refrigerant builds up to a considerable depth and the imperforate portions of the side walls retain the refrigerant within the container.

Fig. 5 shows a baffle plate 70 extending upwardly at (85) substantially to the top 40 of the tank 6. The top 40 is preferably secured to the baffle plate 70 by some means to prevent deflection of the top 40. The securing means may be stud bolts 87 secured to the baffle plate 70 and extending through the top and nuts 88 on the stud bolts tightened against the top 40. The baffle plate has a lower portion 89 below the opening 48 to facilitate the loading of refrigerant into the tank.

The tank 6 may be supported in the car by any convenient means. The means shown comprises carlines 93, which may be channels with their webs vertical, extending between and secured to the side walls 3. The carlines 93 have secured thereto outstanding brackets 94, preferably having substantially horizontal surfaces 96. The tank 6 has secured to the ends thereof outstanding brackets 97, preferably having substantially horizontal surfaces 98 adapted to engage in flatwise relation the surfaces 96 of the brackets 94. Bolts or rivets may be used to secure together the brackets 94, 97. Longitudinally extending members may be used in place of the tank brackets 97 to support the tank, which members may extend between the carlines 93 and be secured to the side walls 29 of the tank 6.

The top 40 of the tank 6 is preferably disposed in spaced relation to the roof 2 of the car and may be inclined at a different angle as shown in Fig. 1. This arrangement is to permit ventilating air to flow through the hatch 5 and into the lading compartment 18. A wire screen 99 is preferably provided to prevent passage of solid refrigerant.

It is readily apparent from Fig. 2 that the tank 6 is comprised of an upper and a lower portion. The lower portion comprises the bottom 28, side walls 29 and end walls 32 secured together with relative permanence by the rivets 36. The upper portion is secured to the lower portion preferably by the bolts 45, 46 and may therefore be readily removed for cleaning, repairing or galvanizing.

The accompanying drawings illustrate the preferred form of the invention, though it is to be understood that the invention is not limited to the exact details of construction shown and described, as it is obvious that various modifications thereof, within the scope of the claims, will occur to persons skilled in the art.

I claim:

1. A tank for use in a refrigerator car comprising upper and lower portions, said lower portion comprising a bottom and integrally formed upstanding side walls provided with outstanding marginal flanges on the upper edges thereof and end walls having outstanding peripheral flanges disposed in flatwise relation to said bottom and side walls and fixedly secured thereto, said upper portion comprising a top having depending side marginal flanges and outstanding reflanges engaged flatwise with the side wall flanges and means to removably secure said reflanges to said side wall flanges and said top to said peripheral flanges.

2. A tank for use in a refrigerator car comprising upper and lower portions, said lower portion comprising a bottom and upstanding side walls

provided with outstanding marginal flanges on the upper edges thereof and end walls having outstanding peripheral flanges disposed in flatwise relation to said bottom and side walls and fixedly secured thereto, said upper portion comprising a top having opposite depending side marginal flanges of equal depth and outstanding reflanges engaged flatwise with the side wall flanges and means to removably secure said reflanges to said side wall flanges and said top to said peripheral flanges, said top and bottom being disposed in planes converging toward one of said side walls, one of said side walls having apertures therein immediately below the outstanding marginal flange.

3. A tank for use in a refrigerator car comprising upper and lower portions, said lower portion comprising a bottom and upstanding side walls provided with outstanding marginal flanges on the upper edges thereof and end walls having outstanding peripheral flanges disposed in flatwise relation to said bottom and side walls and secured thereto, said upper portion comprising a top having depending side marginal flanges and outstanding reflanges engaged flatwise with the side wall flanges, a hatch opening in said top and means to secure said reflanges to said side wall flanges and said top to said peripheral flanges and a substantially vertical baffle plate extending between and secured to opposite walls, said baffle plate having a part of the upper edge thereof secured to said top for stiffening the top and another part of said upper edge below said hatch opening spaced below the level of said top.

4. A refrigerant container adapted for use in a refrigerator car comprising a bottom and upstanding spaced apart side and end walls, said bottom and walls being substantially imperforate except for apertures in at least one of said side walls in spaced relation to said bottom, each of said apertures being spaced from said end walls a distance at least one-fourth of the distance between end walls.

5. A refrigerant container adapted for use in a refrigerator car comprising a bottom and upstanding spaced apart side and end walls, said bottom and walls being substantially imperforate

except for apertures in at least one of said side walls in spaced relation to said bottom, said apertures being confined to portions of the side walls having lengths not greater than one-half the distance between the end walls, said portions being disposed substantially midway between said end walls.

6. A refrigerant container adapted for use in a refrigerator car wherein a drip pan is spaced below the bottom of the container to catch overflowed liquid and to form a passage which comprises part of the cold air circulating system, said container comprising a bottom and upstanding spaced apart side and end walls, said bottom and walls being substantially imperforate except for apertures in one or both of said side walls in spaced relation to said bottom, each of said apertures being spaced from said end walls a distance at least one-fourth of the distance between end walls.

7. A refrigerant container adapted for use in a refrigerator car comprising a bottom and upstanding spaced apart side and end walls and a substantially vertical baffle extending between and secured to said end walls, said bottom and walls being substantially imperforate except for apertures in one or both of said side walls in spaced relation to said bottom, each of said apertures being spaced from said end walls a distance at least one-fourth of the distance between end walls.

8. A refrigerant container adapted for use in a refrigerator car comprising a bottom and upstanding spaced apart side and end walls, a substantially vertical baffle extending between and secured to said end walls and a second baffle intersecting the first mentioned baffle and extending between and secured to said side walls, said bottom and walls being substantially imperforate except for apertures in one or both of said side walls in spaced relation to said bottom, each of said apertures being spaced from said end walls a distance at least one-fourth of the distance between end walls.

CHARLES D. BONSALL.
